UNITED STATES PATENT OFFICE.

JOHN LIPPS, OF MONTOUR, IOWA.

CHECKREIN-SUPPORT.

1,111,475.

Specification of Letters Patent. Patented Sept. 22, 1914.

Application filed February 28, 1914. Serial No. 821,758.

To all whom it may concern:

Be it known that I, JOHN LIPPS, a citizen of the United States, residing at Montour, in the county of Tama and State of Iowa, have invented a new and useful Checkrein-Support, of which the following is a specification.

The present invention relates to improvements in a check rein support, one object of

10 the present invention being the provision of a two-part member carrying a check rein guiding roller, such parts being normally held in guiding position by means of the throat strap of a bridle, whereby the support 15 may be readily detached to permit of the easy direction or insertion of the check rein therein without disengaging the rein from the bridle or disconnecting the sections thereof.

20 A further object of the present invention, is the provision of a check rein support or guide, in which two members are provided, one end of each of which is apertured and curved to fit co-extensively upon one another, one of said members constituting a buckle to receive the terminal of the throat strap of a bridle to properly hold the sections together and at the same time support it from the bridle.

25 30 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

35 40 In the drawings—Figure 1 is a view in perspective showing the present check rein support or guide in use. Fig. 2 is a longitudinal sectional view through the complete device and the portion of the throat strap attached thereto. Fig. 3 is a perspective view of the complete device *per se*.

45 50 Referring to the drawings, the support or holder 1 includes one member 2 provided with the curved and flattened apertured end 3 and with the reduced terminal 4. The other member 5 is provided with the en-

larged flattened and curved portion 6 which is adapted to rest upon and fit co-extensively with the portion 3 of the member 2, its bar 7 being disposed across the slot thereof to 55 constitute a strap guide, while a stationary pin 8 is provided to engage one of the apertures of the throat strap 12 so that the present device may be adjustably held in position. The reduced terminal 9 of the member 5 is adapted to coöperate with the reduced member 4 of the member 2 and receive the journaling pin or rivet 10 for the check rein guiding roller 11. By this means the two members are properly assembled but 60 due to the pivot 10 are permitted sliding movement from one side to the other so that the check rein 13 may be properly positioned therebetween without the necessity of the disconnection thereof from the bit. 70

In use it will be noted, as in Fig. 2, that the terminal of the throat strap 12 is fed through from the under side so as to pass over the bar 7 so that one of the apertures of the strap will be upon the pin 8, the terminal of the strap being projected upon the opposite side of the bar 7 and downwardly below the member 2, the terminal 4 of the member 2 being so curved as to permit of this arrangement, so that the roller 11 will 80 be properly supported away from the animal adjacent to the throat strap. 75

What is claimed is:

1. A check rein support, composed of two members, each of which is provided with a 85 long terminal, and a roller journaled between the terminals, one of the members having a flat apertured end while the other has a buckle formed in the corresponding end, whereby the terminal of a throat strap 90 may engage the buckle to hold the members together.

2. A check rein support composed of two members, each of which is provided with a long terminal, a journaling pin holding the 95 long terminals together, whereby the members may swing with the pin as the axis, and a roller mounted upon the pin and disposed between the terminals and holding such terminals spaced, one of the members being 100 provided with a flat apertured end while the other member is provided with a buckle.

for disposition adjacent the apertured end of the other member, and whereby the terminal of a throat strap may engage the buckle and the under side of the apertured 5 end of the other member to hold the members against swinging movement.

In testimony that I claim the foregoing as

my own, I have hereto affixed my signature in the presence of two witnesses.

JOHN LIPPS.
